(57) CLAIM

The ornamental design for a clothes hook, as shown and described.

DESCRIPTION

FIG. 1 is a first perspective view of the clothes hook showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a front view thereof showing the clothes hook in an alternate state.

The broken lines shown in the drawings depict portions of the clothes hook that form no part of the claimed design.
